(57) **CLAIM**

The ornamental design for a display screen or portion thereof with animated graphical user interface as shown and described.

DESCRIPTION

FIG. 1 is a front view of a display screen or portion thereof with animated graphical user interface showing a first image of my new design.

FIG. 2 is a second image thereof.

FIG. 3 is a third image thereof.

FIG. 4 is a fourth image thereof.

FIG. 5 is a fifth image thereof.

FIG. 6 is a sixth image thereof.

FIG. 7 is a seventh image thereof.

FIG. 8 is an eighth image thereof; and,

FIG. 9 is a ninth image thereof.

The appearance of the animated graphical user interface sequentially transitions between the images shown in FIGS.

1, 2, 3, 4, 5, 6, 7, 8, and 9. The process or period in which one image transitions to another forms no part of the claimed design.

The grayscale in the figures indicate a contrast in appearance. The outer broken lines in the figures show a display screen or portion thereof and form no part of the claimed design. The other broken lines in the figures show portions of the animated graphical user interface that form no part of the claimed design.
